Primary Examiner—Marianne N Pandozzi

(74) Attorney, Agent, or Firm—Craig A. Fieschko, Esq.;
DeWitt Ross & Stevens S.C.(57) **CLAIM**

I claim the ornamental design for a plunger pot, as shown.

DESCRIPTION

FIG. 1 is a perspective view of a plunger pot showing my design;

FIG. 2 is a front side elevational view thereof;

FIG. 3 is a right side elevational view thereof, the left side being a mirror image thereof; and,

FIG. 4 is a top plan view thereof.
